INVENTOR
GEORGE SEYMOUR

By D. F. Vaughan Atty.

UNITED STATES PATENT OFFICE.

GEORGE SEYMOUR, OF HARROW, ENGLAND.

MACHINERY FOR DECORTICATING THE LEAVES OF FIBROUS PLANTS.

Application filed June 2, 1926, Serial No. 113,235, and in Great Britain January 19, 1925.

This invention relates to machinery for decorticating or extracting the fibres from the leaves of various fibre-plants, such as manila, sisal, coir, Indian hemp, ramie and so forth. The present invention is specially applicable to the elongated spiky sisal leaves (*Agave sisalana*) to remove the meaty or pulpy green bulk and to obtain the small percentage of fibrous material.

Machines of this type usually include a drum or drums of cast iron provided on their peripheries respectively with a plurality of circumferentially spaced decorticator knives of angular section. Said drum rotates over a "concave" or bed of phosphor-bronze, and the leaves are fed between the drum and bed whereby all the extraneous body is stripped from the fibrous skeleton.

The present invention is directed particularly to an improved formation of the contacting bed-plate. Its object is to obtain a greater percentage of fibre per leaf.

This object is effected by replacing the usual concave quadrant or arcuate bed-plate by a strip or blade member. This is of phosphor-bronze or the like, and disposed in an inclined position across the periphery of the drum. It is equally spaced away therefrom and as, by virtue of its inclination, it follows to an extent the circumferential curve of the drum, it is accordingly helically bent to conform to this shape.

In order that the said invention may be readily understood, reference is directed to the following description and accompanying drawings, wherein:

Figure 1 is an end view of a drum and two diametrically opposite bed-plate bars, and associated fittings, shown, for example, as employed in the construction of a decorticator according to my co-pending application No. 113,234.

Figure 2 is a development of the bed-plate, and portions of the supporting frames.

In the drawings, 1, 1 represent the side longitudinal chassis frames of a vehicle, as this invention is particularly applicable to such a mode of mounting as set forth in my said co-pending application. The drum 2 is rotatably mounted between cross bearers 3 carried by side brackets 4 supported on the chassis frames 1, 1. On the periphery of the

drum a suitable number of knives 5 are fixed (which, if desired, may be inclined across the periphery from side to side).

The said improved bed-plate, or more correctly bed-bar 6, may be of any suitable section, and may present a rounded, flat or angular edge facing the drum. For example, it may be of square or rectangular section.

When a bed-bar of this nature is mounted across two curved side frames 7, 7 concentric with the drum 2, the parts of the leaves which have been stripped can hang over the bed-bar away from the area of decorticating action, and so the fibres will not be unduly damaged as the leaf is further fed in.

The bed-bar 6 may be adjustable with relation to the drum 2 in any convenient manner, for instance, by mounting the bed-bar carrier 8 slidably at 9 in the frames 7, 7.

In the drawings, the numeral 10 indicates a gripping conveyor guide forming no part of the present invention, and more particularly described in the said co-pending application.

It is preferred to employ a plurality of bed-bars 6, (such as two diametrically opposite) operating in accordance with the said co-pending application, and, as illustrated, the mounting of another one underneath the drum is similar to the mounting hereinbefore described, similar reference numerals indicating corresponding parts.

It will be apparent that the present invention results in lightness of construction, and in this respect it is particularly applicable to the transportable decorticating plant described in my co-pending application No. 113,235 of even date hereof. It is, however, applicable to most or many types of decorticators.

I claim:

1. In a machine for decorticating leaves of fibrous plants, spaced side members, a drum rotatably mounted between said members, knives on said drum, and a narrow strip-like helical bed-bar mounted on said side members.

2. In a machine for decorticating leaves of fibrous plants including spaced side members having guides, a drum rotatably mounted between said members, knives on said drum, and a narrow strip-like bed-bar

having straight parallel side edges and arranged obliquely between said side members and conforming to the curvature of the drum, parallel supporting members carried by the underside of the bed-bar and slideable in the guides, and adjusting screws carried by the side frame members and en-

gaging the bed-bar for adjusting the same radially to the axis of the drum.

In testimony whereof I have affixed my ¹⁰ signature hereto this 19th day of April, 1926.

GEORGE SEYMOUR.
